UNITED STATES PATENT OFFICE.

SIDNEY W. HETHERINGTON, OF LOUISVILLE, KENTUCKY, ASSIGNOR TO ANCHOR STOVE & RANGE CO., OF NEW ALBANY, INDIANA.

DESIGN FOR A CABINET HEATER.

Application filed January 8, 1925. Serial No. 11,960. Term of patent 3½ years.

To all whom it may concern:

Be it known that I, SIDNEY W. HETHERINGTON, a citizen of the United States, residing at Louisville, in the county of Jefferson and State of Kentucky, have invented a new, original and ornamental Design for Cabinet Heater, as shown in the accompanying drawing and described in the following specification.

The drawing is a perspective view of my cabinet heater.

I claim:

The ornamental design for a cabinet heater as shown.

SIDNEY W. HETHERINGTON.
